By E. S. Knight, Bro
Atty's

UNITED STATES PATENT OFFICE.

THOMAS S. EVANS, OF ST. LOUIS, MISSOURI.

DESIGN FOR A WOOD-STOVE.

SPECIFICATION forming part of Design No. 24,186, dated April 9, 1895.

Application filed November 13, 1894. Serial No. 528,698. Term of patent 3½ years.

To all whom it may concern:

Be it known that I, THOMAS S. EVANS, a citizen of the United States, residing at the city of St. Louis, in the State of Missouri, have invented and produced a new and original Design for Wood-Stoves, of which the following is a specification, reference being had to the accompanying drawing, forming part hereof.

The drawing is a perspective view showing my design.

The leading features of my design consist in the stove, provided with a lower door, which is of trough shape, and the feed opening which is of cylindrical shape surmounted by an ornamental vase.

1 is the elliptical body surmounted at top by a feed-opening 9 of cylindrical shape pro-

vided with a cover in the form of an ornamental vase 2. At the rear of the feed opening also surmounting the top is a collar 3 of cylindrical shape for the attachment of a smoke-pipe.

4 is a trough shaped door, at the lower part of the front of the body, having a flat top 5, inclined front 6, and angular ends 7.

8 are ornamental legs.

Having thus described my invention, the following is what I claim as new therein and desire to secure by Design Letters Patent:

The design for a wood-stove; substantially as herein shown and described.

THOMAS S. EVANS.

In presence of—

E. S. KNIGHT,
N. FINLEY.
